(57) **CLAIM**

The ornamental design for an electronic device with graphical user interface, as shown and described.

DESCRIPTION

The sole FIGURE is a front view of an electronic device with graphical user interface showing the claimed design. The peripheral dashed broken lines depict a display screen or portion thereof, and form no part of the claimed design. The interior broken lines depict portions of the graphical user interface which form no part of the claimed design. Within the peripheral dashed broken lines, the dashed line rectangle and the half-tone portion within form no part of the claimed design.
